UNITED STATES PATENT OFFICE.

JOSEPH F. CHATELLIER, OF NEW YORK, N. Y.

DESIGN FOR JEWELRY.

SPECIFICATION forming part of Design No. 12,180, dated March 1, 1881.

Application filed January 21, 1881. Term of patent 7 years.

To all whom it may concern:

Be it known that I, JOSEPH F. CHATELLIER, of the city, county, and State of New York, have invented a new and Improved Design for 5 Jewelry, of which the following is a full, clear, and exact description.

In the drawings, Figure 1 is a face view, and Fig. 2 a side view in large size, of a stud or button having my newly-designed ornamentation.

My invention relates to the ornamentation of surfaces of articles of jewelry; and the design consists of the tortile figures *a*, which are raised threads on the surface of the button *A*. 15 These tortile figures are of comparatively small size, and are placed as closely together as may be, so that the appearance to the eye is that of

an involved thread ornamentation or a stippled surface, which is increased by the raised figures being banded to resemble threads. 20 When applied to a plain surface the effect is highly ornamental, rich, and pleasing.

The figures may vary in size, if desired.

Having thus fully described my invention, I claim as new and desire to secure by design- 25 patent—

The design for surface ornamentation of jewelry, consisting of a threaded surface formed by aggregated tortile figures, substantially as shown and described.

JOS. F. CHATELLIER.
